(57) **CLAIM**

The ornamental design for an aerodynamic flying disc, as shown and described.

DESCRIPTION

FIG. 1 is a bottom perspective view of the aerodynamic flying disc of the instant invention;

FIG. 2 is a top perspective view thereof;

FIG. 3 is a bottom plan view thereof;

FIG. 4 is a top plan view thereof;

FIG. 5 is a front elevation view thereof;

FIG. 6 is a rear elevation view thereof;

FIG. 7 is a right side elevation view thereof; and,

FIG. 8 is a left side elevation view thereof.

1 Claim, 2 Drawing Sheets

FIG. 1

FIG. 2

FIG. 3**FIG. 5****FIG. 6****FIG. 4****FIG. 7****FIG. 8**
